UNITED STATES PATENT OFFICE

2,037,551

IRONING PRESS

John S. Visscher, Bridgeport, Conn., assignor to
General Electric Company, a corporation of
New York

Application June 19, 1935, Serial No. 27,369

10 Claims.

(Cl. 68—9)

The present invention relates to ironing presses of the type in which ironing is effected by the pressure between a pair of cooperating pressing members.

5 The object of my invention is to provide an improved construction and arrangement in ironing presses of this type for developing the pressure between the pressing members. For a consideration of what I believe to be novel and my 10 invention, attention is directed to the accompanying description and the claims appended thereto.

In the accompanying drawing, Fig. 1 is an end elevation of an ironing press embodying my invention, the base being partly broken away to show the construction and manner of supporting the carriage; Fig. 2 is an end elevation of the shoe and the upper arm of the carriage, partly in section to show the pressure developing mechanism; Fig. 3 is a sectional view taken on line 3—3 of Fig. 2; Fig. 4 is a top plan view of the pressure developing mechanism shown in Fig. 2; and Fig. 5 is a view similar to Fig. 2 showing the pressure developing mechanism in a position in which the shoe is moved into contact with the buck.

Referring to the drawing, the pressing members comprise a heated shoe 1 and a padded buck 2. The buck is suitably supported on a raised portion 3 of a hollow base 4. The buck is rectangular in shape, and the upper surface of the buck is inclined upwardly from the front so that the clothes to be ironed may be more conveniently arranged on the buck. At the rear of the buck, the top wall of the base is raised to provide an apron 5 which prevents the surplus of the material being ironed from falling over the rear edge of the base.

40 The numeral 6 indicates a U-shaped carriage for supporting the shoe and for moving the shoe into and out of register with the buck. The cross section of the arms of the carriage is channel shaped, as shown in Fig. 3, and comprises flanges 7 which are connected by a web 8. The lower arm 9 of the carriage is pivotally supported on the base on a rod 10 carried between the side walls 11 of the base. The rod 10 fits within inclined 45 elongated slots 12 which are formed in the flanges 7. The front end of arm 9 is provided with a notch 13 which is adapted to engage a rod 14, likewise carried between the side walls of the base. The upper side of the notch 13 is extended 50 to provide a stop 15 which prevents movement of

the arm 9 past the rod 14. When the carriage is in the position shown in Fig. 1, it is locked in the position shown and cannot be displaced by forces perpendicular to the face of the shoe. The carriage may be pivoted rearwardly to move the 5 shoe out of register with the buck by sliding the carriage rearward until the notch 13 is clear of the bar 14, and then pivoting the carriage on rod 10. The elongated slots 12 permit this rearward sliding movement. The base is provided 10 with spaced guides 16 which engage both sides of the arm 9 and guide the pivotal and sliding movement of the carriage.

The shoe is supported on the upper arm 17 of the carriage, as shown in Fig. 3, by brackets 18 15 which are fixed to the inner side of flanges 7. Each of the brackets carries a bushing 19 within which slides a stud 20. The lower end of each stud is threaded into the upper side of the shoe, and at the upper end of each stud is a washer 21, which is held in place by a pin 22. Coil springs 23, surrounding the studs 20 and arranged between the brackets 18 and the washers 21, bias the shoe toward the lower side of the arm 17. Cylindrical sleeves 24 which are fixed to the brackets 18 enclose the springs. This arrangement 25 permits the shoe to be moved relative to the carriage and also permits tilting of the shoe to accommodate unequal thickness of the material being ironed.

30 The pressure developing mechanism for moving the shoe away from the carriage into pressing engagement with the buck comprises a link 25 which is pivoted on a rod 26 carried by a bracket 27 at the front end of arm 17. The link 25 comprises a pivoted member 25a to each edge of which is fixed a side plate 28. Between the side plates 28 extends the lower end of an operating lever 29 which is pivoted on a pin 30, fixed between the side plates 28. The operating lever 29 35 is normally held in fixed relation to the link 25 by pins 31 (see Fig. 4), which are carried by the lever and which are urged by a spring 32 into notches 33 on the inner side of plates 28. The lower end of the operating lever projects beyond 40 pin 30, and the projecting end 34 is provided with a pin 35 on which a roll 36 is rotatably carried by an anti-friction bearing. The roll 36 contacts with the upper surface of a plate 37 which is fixed to the shoe. At the right-hand end of link 45 25 is a pawl 38 which is pivoted on a pin 39 fixed between flanges 28. The pawl is urged in a clockwise direction by a spring 40 arranged between a pin 41 on one of the plates 28 and a pin 42 projecting from the pawl. The pawl is held against 50 55

movement by the spring 40 by a pull link 43 connected at one end to pin 42 and having the other end 44 bent to extend behind the operating lever 29. As long as the pins 31 hold the operating lever 29 in fixed relation to the link 25, the pawl is held in the position shown in Fig. 2. While the lever 29 and the link 25 are held in fixed relation, movement of the lever 29 in a clockwise direction, as viewed in Fig. 2, causes the link 25 to be pivoted in a clockwise direction about the rod 26, thereby causing the roll 36 to force the shoe away from the carriage and into contact with the upper surface of the buck, as shown in full lines in Fig. 5. As soon as the pressure between the buck and the shoe reaches a predetermined value, the resistance offered to movement of link 25 is such that the pins 31 move from the notches 33, and the lever 29 pivots in a clockwise direction about the pin 30. As shown in Fig. 5, this movement permits the pawl 38 to be moved in a clockwise direction by spring 40 and thereby to engage one of the notches 45 in a plate 46. The plate 46 is supported by an inclined bracket 41 which is fixed to the flanges 7 of the upper arm of the carriage and to ears 48 which are struck up from the web of the upper arm of the carriage. As soon as the pawl has been moved by the spring 40 to the position shown in Fig. 5, the link 25 is locked to the carriage in the position shown. Further clockwise movement of the lever 29 causes the lever to pivot about the pin 30, and the roll 36 to move the shoe into final pressing engagement with the buck. The dotted lines in Fig. 5 show the start of this movement. Roll 36 acts as a cam during this latter movement of the lever. By this arrangement the leverage exerted by the lever 29 is increased so that the final pressing engagement requires less effort. In other words, during the time when the lever 29 and link 25 move together, the pressure developing mechanism may be considered as a relatively low pressure mechanism which will quickly move the shoe into contact with the buck. When the lever 29 pivots on the link 25, the pressure developing mechanism is relatively a heavy pressure mechanism by which the operator can easily develop the required ironing pressure between the buck and the shoe. The position to which the link 25 is moved during the initial movement of the operating lever 29 depends upon the pressure developed between the buck and the shoe so that variations in the thickness of the material being ironed are inherently compensated for. At the end of the clockwise movement of lever 29, the roll 36 is moved to the left of pin 30 so that the reaction of the pressing forces holds the roll in this position. The end of member 25a provides a stop which limits the movement of the lever 29.

To relieve the pressure between the buck and the shoe, the operating lever 29 is rotated in a counter-clockwise direction returning the lever to the position shown in Fig. 2. In this position, the pins 31 are slightly to the right of the notches 33 in the plates 28, and the pressure between the buck and the shoe is substantially decreased. A slight additional counter-clockwise movement of the operating lever will cause the link 43 to disengage the pawl 38 from the plate 46 and cause the pins 31 to be again seated in the notches 33. In this position, the springs 23 will cause the shoe and the link 25 to be returned to the position shown in Fig. 2.

The pressure developing mechanism is enclosed by a cover 49 fixed to the upper arm of the car-

riage, and a handle 50 secured to the cover is provided for moving the shoe into and out of register with the buck.

In the use of the ironing press, the material to be ironed is arranged on the upper surface of the padded buck 2, and the shoe is moved to the position shown in Fig. 1 by means of the handle 50. In this position, the shoe is in register with and in spaced relation to the buck, and the carriage is locked in position so that it cannot be displaced by forces perpendicular to the face of the shoe. While holding the handle 50, in order to prevent rearward sliding of the carriage, the operating lever 29 is moved in a clockwise direction, as viewed in Fig. 2. During the initial part of this movement, the lever 29 and the link 25, which are held in fixed relation by the pins 31, rotate about the rod 26 and quickly move the shoe into contact with the buck. As soon as the pressure between the buck and the shoe reaches a high enough value, the pins 31 can no longer maintain the lever 29 and the link 25 in fixed relation. At this time the pins 31 move out of the notches 33, and the lever 29 then pivots about the pin 30. During the initial pivoting movement of the lever 29 about the pin 30, the pawl 38 is moved in a clockwise direction by spring 40 from the position in Fig. 2 to the position in Fig. 5. In this position, the pawl engages one of the notches 45 in plate 46 and locks the link 25 in position. Further clockwise movement of the lever 29 now causes the roller 36 to move the shoe into final pressing engagement with the buck. At the end of the clockwise movement of the lever 29, the roll 36 is moved to the left of the pin 30 so that the reaction of the pressing forces holds the parts in this position. The end of member 25a provides a stop which limits the movement of the lever 29.

As explained above, the pressure between the buck and the shoe is relieved by rotating the lever 29 in a counter-clockwise direction, returning the lever to the position shown in Fig. 2. At the end of this return movement, the pins are returned to the notches 33, and the link 43 rotates the pawl 38 in a counter-clockwise direction disengaging the pawl from the plate 46. The upper surface of the buck may now be uncovered by pushing rearwardly on the handle 50 so that the notch 13 of the carriage moves clear of the rod 14 in the base and then pivoting the carriage rearwardly on the rod 10.

What I claim as new and desire to secure by Letters Patent of the United States is:

1. An ironing press comprising a pair of pressing members, low pressure means including a part for moving one of said pressing members into pressing engagement with the other pressing member, means controlled by the pressure between said members for locking said part in the position to which it is moved by said low pressure means, and heavy pressure means carried by said part for moving said first pressing member into final pressing engagement with the other pressing member. 55

2. An ironing press comprising a pair of pressing members, means for relatively moving said pressing members into register with each other, a lever having a predetermined travel for relatively moving said pressing members into pressing engagement, and means responsive to the pressure between said pressing members for increasing the leverage of said lever whereby the pressure between said pressing members will be 60 70 75

- substantially independent of the thickness of the material being ironed.
3. An ironing press comprising a buck, a shoe, an arm carrying said shoe, a link pivoted to said arm for moving said shoe relative to said arm and into contact with said buck, means responsive to the pressure between said buck and said shoe for locking said link to said arm, and means pivoted on said link for moving said shoe into final pressing engagement with said buck.
4. An ironing press comprising a buck, a shoe, an arm carrying said shoe, a link pivoted to said arms, a lever pivoted to said link for moving said shoe relative to said arm into contact with said buck, a connection between said lever and said link for holding said lever and link in fixed relation, said connection releasing responsive to a predetermined pressure between said buck and said shoe, a latch for locking said link to said arm, and means operated by further movement of said lever for moving said shoe into final pressing engagement with said buck.
5. An ironing press comprising a buck, a shoe, an arm carrying said shoe, means including a member carried by said arm and movable relative thereto for moving said shoe into contact with said buck, means responsive to the pressure between said buck and said shoe for locking said member to said arm, and means pivoted on said member for moving said shoe into final pressing engagement with said buck.
6. An ironing press comprising a buck, a shoe, an arm carrying said shoe, means for initially moving said shoe relative to said arm into contact with said buck, a member movable to a position dependent upon the position of the shoe at the end of the initial movement, means responsive to the pressure between the buck and the shoe for locking said member in this position, and pressure developing mechanism between said
- member and said shoe for moving said shoe into final pressing engagement with said buck.
7. An ironing press comprising a buck, a shoe, an arm carrying said shoe, means including a member carried by said arm and movable relative thereto for moving said shoe into contact with said buck, means responsive to the pressure between said buck and said shoe for locking said member to said arm, and pressure developing mechanism between said member and said shoe for moving said shoe into final pressing engagement with said buck.
8. An ironing press comprising a buck, a shoe, an arm carrying said shoe, a lever carried by said arm for moving said shoe relative to said arm into pressing engagement with said buck, and means responsive to the pressure between said buck and said shoe for increasing the leverage of said lever whereby the pressure between the buck and the shoe may be more readily increased.
9. In an ironing press comprising a pair of pressing members, means for effecting initial contact of the pressing members, a part movable to a position dependent upon the position of the pressing members at the initial contact, means responsive to the pressure between the presents members for locking said part in this position, and pressure developing mechanism carried by said part for effecting final pressing engagement of the pressing members.
10. In an ironing press comprising a pair of pressing members, a support, means including a link pivoted to said support for effecting initial contact of the pressing members, means responsive to the pressure between the pressing members for locking said link to said support, and means carried by said link for effecting final pressing engagement of said pressing members.

JOHN S. VISSCHER. 40

CERTIFICATE OF CORRECTION.

Patent No. 2,037,551.

April 14, 1936.

JOHN S. VISSCHER.

It is hereby certified that error appears in the printed specification of the above numbered patent requiring correction as follows: Page 3, first column, line 13, claim 4, for "arms" read arm; and second column, line 26, claim 9, for "presents" read pressing; and that the said Letters Patent should be read with these corrections therein that the same may conform to the record of the case in the Patent Office.

Signed and sealed this 19th day May, A. D. 1936.

Leslie Frazer
